ABSTRACT

Process of preparing lubricating oils of improved quality stability in color and sludge formation of oils hydrogenated at temperatures above 650° F. by serially extracting same subsequent to hydrogenation with a solvent having preferential solubility for aromatics.

19 Claims, No Drawings

STABILIZING A HYDROCRACKED LUBE OIL BY SOLVENT EXTRACTION

CROSS REFERENCES TO RELATED APPLICATIONS

This application is a continuation-in-part of U.S. Pat. application Ser. No. 875,502, filed Nov. 10, 1969 by Sheldon L. Thompson, which in turn is a continuation-in-part of U.S. Pat. application Ser. No. 530,580, filed Feb. 28, 1966, by Sheldon L. Thompson, both now abandoned.

BACKGROUND OF THE INVENTION

This invention broadly relates to the improvement in quality stability of lubricating oils. It is more particularly related to improving the stability of lubricating oils which have been hydrogenated under certain conditions, against degradation in color and sludge formation which results when such are exposed to actinic radiation and oxygen. Still more particularly, the invention relates to solvent extraction of hydrocracked lubricating oil stocks to substantially improve the color and sludge problems.

Various processes have been used from time to time for upgrading lubricating oil stocks. These have generally involved either solvent extraction or hydrogenation including hydrocracking treatment. In more recent times, there has been a demand for lubricating oils having an increased viscosity index. Recent developments in hydrocracking techniques in particular, or hydro-treating techniques, as some prefer to call it, has spawned and increased interest in commercial utilization of such hydrogenation processes as a lubricating oil stock upgrading method to obtain lubricating oils with an increased viscosity index. Generally the viscosity index of the full range lube fraction dewaxed to a 0° F. pour point product lube oil will be 115 or higher. Briefly, this has involved catalytic hydrocracking of the lubricating oil stock at a temperature on the order of about 650° F. and above at high pressures. While such processes have greatly enhanced the viscosity index of the lubricating oil stocks so treated, they have simultaneously caused said stocks to exhibit a marked increase in color degradation on exposure to ultraviolet light and also to form greater amounts of sludge in the presence of oxygen during such exposure. It would be highly advantageous and, consequently, it is desirous to provide a method for alleviating these problems of quality stability.

It is, therefore, the main object of the present invention to substantially reduce the extent of color degradation in lubricating oil stocks which color problems occur upon exposure of a hydrotreated oil to actinic radiation, such as ultraviolet light and oxygen. It is another object to reduce the sludge-forming characteristics of a lube oil under such conditions. Other objects are to prepare lubricating oils in high yields, having a high viscosity index, and of improved stability. It is a still further object to accomplish each of the foregoing objects, in an economical fashion. It is yet another object to accomplish the foregoing objects by a simple and expedient process requiring simple, conventional and inexpensive equipment. Other objects will become apparent from the comments found herein.

SUMMARY OF THE INVENTION

To the accomplishment of the foregoing and related

ends, a lubricating oil stock which has been hydrocracked or hydrotreated at a temperature above about 650° F. under high pressures, i.e., generally at 500 p.s.i. and above, is treated according to this invention, said treatment comprising extracting said lubricating oil stock in at least two stages with a solvent having preferential solubility for aromatic compounds at a temperature below the miscibility temperature which is generally below about 300° F. and above the temperature at which solids are formed. While the foregoing is the invention in its broadest aspect, yet another broad aspect constitutes the preparation of lubricating oils having a high viscosity index and good quality stability in regard to both color and sludge in the presence of ultraviolet radiation and oxygen, which comprises, in combination, hydrocracking or hydrotreating a lubricating oil stock followed by successive extractions of the so-treated lube oil stock with a selective solvent having a preferential solubility for aromatics in not less than two extraction stages at a temperature below the miscibility temperature which is generally below about 300° F. and a temperature above that at which solids are formed.

It has been observed by many workers that lubricating oil stocks exhibit a degree of quality instability in the presence of actinic radiation, particularly ultraviolet light, and oxygen. Specifically, they tend to form sludge upon exposure to oxygen and actinic radiation. It has been noticed by many workers that lubricating oil stocks which have been hydrogenated and especially where hydrocracked, are improved in properties in many respects but are also found to experience significant difficulties of this nature. I have found that these problems are caused by some aromatic compounds of unknown specific structures. I have found that the troublesome configuration probably involves multiple rings. The surprising part of this is that hydrogenation processes, particularly the more recent ones, for example, as defined in U.S. Pat. Nos. 2,779,711; 2,917,448; 2,960,458; 3,046,218; 3,078,238 and 3,078,221, experience this problem despite the fact that certain color bodies are destroyed by such hydrogenation processes and particularly the multiple-ringed aromatics. I have evidence to show that notwithstanding the fact that certain troublesome multiple-ringed configurations are destroyed by hydrogenation processes and especially hydrocracking under the severe conditions employed in same; nevertheless, certain color body and sludge body precursors believed to be of multiple-ringed structure are present following the hydrogenation process when it is conducted at severe conditions including a temperature above about 650° F. These precursors are then able to form color bodies and sludge following the hydrogenation. The problem materials which are present whether they are formed by the hydrogen treatment as is believed to be the case or whether certain inhibitors present theretofore are destroyed by the hydrogenation whereby their inhibiting effect is lost, thereafter exhibit a decided instability in the presence of actinic light and oxygen with the results that quality degradation in regard to both color and sludge occurs. In either case, the result is not achieved if the oil is first extracted and then hydrogenated and the process sequence in a combination hydrogenation and stabilizing selective extraction is accordingly seen to be extremely critical. It is an essential feature of this invention. Different known extractions commonly employed in refin-

ing on the other hand can be performed in their usual sequence including prior to hydrogenation where desired.

HYDROCRACKING

The selective extraction of this invention may be advantageously used in combination with any hydrocracking process which employs temperatures above about 650° F. together with high pressures, those processes defined in U.S. Pat. Nos. 2,917,448; 2,960,458; 3,046,218; 3,078,221; 3,078,238 and 3,088,908 are preferably used, particularly for hydrocracking where such is desired. The teachings of those patents are hereby incorporated by reference.

The feed materials suitable for hydrogenation herein are any heavy petroleum fraction boiling in the lube oil range. In order that lube yields in this step be high the full boiling range hydrocracker charge on a dewaxed to a 0° F. pour point basis generally should have a viscosity index of at least 60 and preferably at least about 75. Generally the full boiling range feed material on a dewaxed to a 0° F. pour point basis will not have a viscosity index of over 100, due to economic consideration. The source of the crude fraction is not critical although other properties are important to the attainment of high lube yields, long catalyst life, etc. Thus the lube source can be any which contains lubricating oil components such as crudes from Pennsylvania, Texas, California, Venezuela or Kuwait.

The hydrocracking process conditions disclosed in U.S. Pat. No. 2,960,458 are particularly preferred for use as the hydrocracking step in the present invention. In brief, this hydrocracking is accomplished by subjecting a deasphalted residuum having a viscosity index of between about 75 and 100 and a viscosity at 210° F. of between 90 and 200 SUS to hydrocracking at the temperature between about 735° and 825° F. and a pressure above about 2,500 p.s.i. and a space velocity of from 0.4 to 1.5. The hydrocracking is carried out in the presence of a catalyst having both aromatic saturation and ring scission activity, for example a nickel sulfide and tungsten sulfide in about a 1:1 to 4:1 ratio. The product from the hydrocracking is subjected to dewaxing (when necessary) and is then distilled to yield components which directly or when blended with each other meet the SAE specification for a multigrade lubricating oil and have a V.I. of about 115 or above. The starting material is a residual petroleum fraction free of asphalt which has a V.I. of from 75 to 100.

SELECTIVE EXTRACTION

It is, of course, known that there are selective solvents for aromatic compounds. It is also known that selective extraction at low temperatures causes the selective solvent to increase its selectivity for aromatics generally. It is, however, not known that such solvents employed at relatively low temperatures would be effective to greatly reduce the color and sludge problem present after the hydrogenation, and in fact would be highly selective for elimination of the color and sludge problems without a great loss in yield as a result of the extraction. It is believed this occurs by selective removal of the precursors.

It has been found that to accomplish the desired results of reduced quality degradation as to both sludge and color, not only is the temperature of the extraction important, but the number of stages is critical. The

number of stages, however, is somewhat dependent on the amount of solvent. It should be kept in mind in any discussion of these two variables that they vary in inverse fashion with respect to each other. When one is increased, the other is to be decreased. It has been dis-

covered that the sludge formation is substantially eliminated in some instances with only two stages but that the color instability is not reduced to the desirable level unless at least about five stages are employed or unless 10 excessive quantities of solvent are employed. While more stages can be employed, it is not contemplated that more than seven stages will be employed primarily because the slight degree of improvement by these added stages does not justify the cost of conducting

15 same and they reduce the yield. Generally from 3 to 7 stages will be found entirely suitable and preferred, and from 5 to 7 stages are most preferred. When utilizing a continuous extraction technique such as a rotating disc contactor or a column the number of stages is determined by empirically comparing the extraction obtained with that obtained using separatory funnels according to the procedure described in the article "Bench Scale Liquid Extraction Techniques" by Edward G. Scheibel, INDUSTRIAL AND ENGINEERING CHEMISTRY, Vol. 49, No. 10, October, 1957, pp. 1679-1684.

20 The ratio of solvent to oil that can be employed in the extraction is not critical and ratios varying over a wide range can be employed; however, advantages are obtained in using certain ratios. Generally, a ratio in excess of 2:1 of a solvent to oil is not employed because such increases the economic cost of the process due to the large volume of the solvent to be handled and a reduction in the yield of lubricating oil product. On the other hand, ratios lower than about 0.25:1 require a compensating increase in the number of stages to achieve the desired effect. Ratios of solvent to oil on the order of from 0.75:1 to 0.5:1 are preferably employed.

25 30 35 40 The temperature, of course, will vary with the particular solvent in a given case. The minimum temperature is usually determined by the dewaxing temperature employed. The reason for this, of course, is that when a temperature below the dewaxing temperature is employed, solids are formed and this is not desired. The temperature is selected in every case to that the extraction stage is entirely in liquid phase. However, generally, a temperature in the range of above about 0° to 300° F. and more usually above about 0° to 250° F. is employed with any of those solvents taught herein. In the case of furfural, which is the most preferred solvent, a temperature in the range above about 0° F. to about 150° F. may be suitably employed; however, a temperature on the order of about 80° to 120° F. is preferred.

45 50 55 The next preferred solvent is acetophenone and substantially the same temperature may be employed with it as the furfural, although the preferred temperature will vary on occasion.

60 65 Other examples of solvents that can be employed in this process are the following, either alone or in a mixture, with or without a selectivity improver:

acetophenone

acetonitrile

nitrobenzene

aniline

2,2'-dichlorodiethyl ether

dimethyl sulfoxide

phenol

The foregoing specifically named solvents are not exhaustive of such solvents since it is contemplated and will be appreciated by those skilled in the art that any solvent having marked preferential solubility for aromatics can be employed in this invention though, of course, not with equal efficiency; and accordingly, all such solvents are not to be regarded as full equivalents.

The apparatus which can be employed to conduct the process is not special and any of the conventional solvent extraction equipment may be employed for same. Illustrative but non-limiting examples are rotating disc contactors, Podbielniak reactors, and countercurrent extraction columns and the like. Of the apparatus aforementioned, I prefer to employ rotary disc contactors or columns in carrying out the invention. It will be appreciated that the extraction can be carried out in either a batchwise operation as well as continuous, although the latter is more convenient and will be generally preferred. The equipment need not be adapted for special pressure conditions because atmospheric pressure is preferred, although atmospheric and superatmospheric pressures can be used.

Having now discussed the invention in broad and general terms and certain features with varying degrees of particularity, it is believed that any further discussion of the invention will be more beneficial in conjunction with detailed working examples. It is to be understood that the examples found hereinbelow are merely illustrative and are not limiting, the same being offered merely to facilitate the understanding of the present invention. It is to be further understood, of course, that the requisite variables are more or less interdependent and particularly the amount of solvent and the number of stages as has been pointed out herein. When one variable is arbitrarily fixed, the limits within which others may be varied are somewhat restricted. The more desirable ranges for ordinary application of my invention are indicated herein, and these can also be ascertained from the specific illustrative examples which include specific illustrative conditions presented herein. However, for any particular application of my invention, the most desirable conditions can be readily determined by routine trial by one skilled in the art, such a determination being facilitated by the discussion of trends of the variables presented herein and in the examples.

It is also to be understood that I am not bound by any theory as to the mechanism of the presence or elimination of the color and sludge problem but only by the claimed process features which produce the effect of their presence or their absence and particularly the latter insofar as the elimination of quality degradation is desired where it occurs and my process discovery does eliminate that problem. The fact that yields of about 97 percent of stable lube oil as based on the unextracted hydrocracked oil can be obtained as illustrated in Example I, below is accounted for by this theory. Such yields are readily obtained by selecting solvent dosages and temperatures which are varied inversely to maintain this yield.

DESCRIPTION OF THE DRAWING

The FIGURE is a diagrammatic flow scheme of a general and basic refinery scheme showing the relative order of the primary steps to be performed in the preparation of lubricating oils according to this invention.

The FIGURE is explained in more detail in conjunction with a working example in Example I.

DESCRIPTION OF THE PREFERRED EMBODIMENTS

EXAMPLE I

HYDROCRACKING REFINING PROCEDURE

Referring now to the FIGURE to facilitate the understanding of the invention and particularly the sequence relationship to the general or basic refining scheme a detailed example will be set forth.

A charge stock of Grade B solvent lube crude mix was charged to crude still 1 and fractionated into approximately 70 percent and 30 percent of overhead and bottoms, respectively. The bottoms had an initial boiling point of 650° F. at atmospheric pressure. The bottoms were charged to a vacuum still 2 and fractionated to produce a gas oil, a distillate stock and a residual asphalt stock; the latter two had initial boiling points of about 695° F. and 750° F., respectively. The residual stock was deasphalting and extracted by the Duo-Sol process (i.e., which employs propane and a mixture of phenol-cresol as solvents) in deasphalting 3 at approximately 130° F. The raffinate from the deasphalting and the distillate stock from the vacuum still when combined had the following properties:

HYDROCRACKER CHARGE PROPERTIES

30	Gravity, °API	30.5
	Vacuum distillation range at 2 mm. adjusted to 760 mm.	
	Int.	694
	5%	760
	10%	784
	30%	829
	50%	881
	70%	964

	Recovery, %	83
	Aniline Pt.	239.2
	SUS/210	59.7
	Avg. M.W.	505
	Wt. % aromatics	22.4
	Waxy V.I.	109
	V.I. dewaxed to 0°F. pour point	about 92

The foregoing mixture was charged to a hydrotreater 4 and said material was hydrocracked in the manner described in U.S. Pat. No. 2,960,458. A refinery hydrogen stream comprising gas and hydrogen, of which about 85 percent was hydrogen, was used in the hydrocracking reaction.

The crude hydrocracked product was charged to a stripper or atmospheric still 5 and fractionated to produce gas, naphtha and fuel oil and a waxy lube of initial boiling point of approximately 700° F. which waxy lube was charged to a dewaxer 6 and dewaxed to a pour point of approximately 0° F. At this point, a product of about 116 viscosity index was obtained. The quality stability is reported below.

STABILIZING EXTRACTION PROCEDURE

Pressed oil from the dewaxer above was then charged to a two-stage furfural rotating disc contactor 7 and was extracted at a temperature of approximately 120° F. using approximately 150 volume percent of furfural to produce a raffinate comprising approximately 97 percent of the charge to the extractor. Although it is preferred that the extractor be located as here in position 7, it can be located in alternate positions shown by 9, 10 or 11 through 14 in the FIGURE. The raffinate

then was distilled to produce three distillate fractions; 1, 2 and 3 and a bright-stock. The properties of these products are as follows:

Distillate	Test method	No. 1	No. 2	No. 3	Bright-stock
Viscosity, SUS/100° F.	D2161	108	219	564	2262

STABILITY TEST PROCEDURE

The distillate fractions then were tested for stability on exposure to ultraviolet light and oxygen. For comparison purposes, tests were made on typical commercial product produced by methods which do include hydrocracking as well as on material produced by the hydrocracking procedure above, but which was not extracted according to the present invention.

The stability test procedure employed was as follows: A 30 ml. sample of the material to be tested was placed in a 100 ml. beaker. Two 275 watt ultraviolet sunlamps were placed approximately 12 inches away from the surface of the sample. The sample was placed in an air ventilated oven on a rotating table and heated to 120° F. The ultraviolet light was turned on when the sample was placed in the oven. After 45 hours, color of the test samples were determined using the ASTM D1500 test. The sludge formed was determined qualitatively by visual observation. The results of the color and sludge tests are reported in Table I as follows:

TABLE I

	Typical commercial product			Product obtained by hydrotreating					
	#1	#2	#3	#1	#2	#3	#1	#2	#3
Distillate fraction	#1	#2	#3	#1	#2	#3	#1	#2	#3
D1500 Int. color	0.5	0.75	1.25	0.25	0.75	1.25	0.25—	0.25—	0.75—
D1500 color after the stability test	2.5	2.5	3.5	5.5	4.5	4.5	3.0	3.0	3.25
Sludge	Light	Haze	None	Heavy	Medium	Haze	Medium	Light	None

EXAMPLE II

Pressed oil product from the Hydrocracking and Refining Procedure of Example I was extracted using the same general procedure as in Example I with acetophenone as the solvent. Five contacts at 100 volume percent dosage and ~80° F. were used.

Using the Stability Test Procedures of Example I, it was found that the oil was decolorized from an initial D1500 color of 1.25 to 0.25 and after 45 hours exposure to U.V. light the color only increased to a D1500 color of 0.5 while untreated charge increased to a color of 5.25.

EXAMPLE III

Pressed oil product from the Hydrocracking Refining Procedure of Example I was extracted with 50 percent by volume of furfural at approximately 80° F. in a number of stages varying from one to five. The stability with regard to color and sludge using the same test procedures as in Example I were determined. The results are reported in Table II below.

TABLE II

Treatment	Charge	1 Stage	3 Stage	5 Stage
		Extraction	Extraction	Extraction
Extraction Temperature, °F.	—	~80°F.	~80°F.	~80°F.
Initial Color, D1500	1.25	0.50	0.25	0.00
D1500 Color after the Stability Test	5.75	4.50	3.75	3.25
Sludge	Medium	Medium	Light	Haze

EXAMPLE IV

A series of three two-stage furfural extraction runs were made at 120° F. on a pressed oil obtained from the procedure in Example I at varying solvent concentrations to determine the general effect of same. Using the test procedures of Example I, the following results were obtained:

Treatment	Charge	50%	100%	150%
		Solvent Dosage A	Solvent Dosage B	Solvent Dosage C
Initial Color, D1500	1.25	0.75	0.50	0.25
D1500 Color after the Stability Test	5.75	4.00	3.50	3.00
Sludge	Medium	Haze	Haze	Haze

EXAMPLE V

Other observations from the experimentation carried out are that a seven-stage extraction of Example I pressed oil at 80° F. employing 150 percent by volume of furfural did not improve the initial color over a five-stage extraction (since it could not improve on a color of 0). However, the seven-stage extraction did effect an improvement in stability over the five-stage extraction. Therefore, initial color is not alone a satisfactory test

TABLE I

Treatment	Charge	Extraction Stages			
		1	3	5	7
Initial color	—	—	—	—	—
D1500	1.75	0.5	0.25	0	0
D1500 Color after Stability Test	4.5	3.0	2.5	≈ 1.5	≈ 1.25

of the advantages of the present invention. Data from which this conclusion is drawn is reported in the table below.

EXAMPLE VI

A furfural extraction carried out at about 170° F. according to the procedure of Example I, and a solvent ratio to oil of 2:1 brought about some improvement in the stability, however, as those skilled in the art know, such conditions are generally not desired with furfural since they result in poorer yield of oil.

EXAMPLE VII

Example VII illustrates that lube oils which have been hydrocracked at above 650° F. suffer from color instability.

Two lube distillate fractions approximating conventional 100 and 500 neutral distillates in boiling range and viscosity were solvent refined at conventional commercial solvent refining conditions with selecto (i.e., a mixture of phenol and cresylic acid). The so-refined distillates were stable according to commercial standards and had the following typical properties:

	500 Neutral	100 Neutral
Viscosity		
SUS/100°F.	523.7	84.75
SUS/210°F.	65.05	38.02
Viscosity Index	99	100
Gravity, °API	30.1	33.8
Boiling Range, °F., 5-95% PT.	777-1012	684-787
Color, ASTM D1500		
Initial	1.25	0.75
Final (after 45 hrs.)	3.25	2.50
Sludge	None	Haze

The foregoing oil fractions were treated with hydrogen under pressure over a sulfided cobalt-molybdenum oxide on alumina catalyst in a series of runs wherein the conditions and resulting stability were as follows:

5	Gravity, °API	32.9
	Sulfur, wt. %	1.26
	SUS/100°F.	52.7
	Pour Point, °F.	-30.0
	O.D. Color	22270

The foregoing charge was vacuum distilled and the heaviest fraction (comprising about 23 percent of the crude) was propane deasphalted (yield of oil about 50 percent) to produce fractions boiling in the ranges below:

15	Light Vacuum Distillate	Boiling Range about 775° to 855°F.
	Heavy Vacuum Distillate	about 855° to 955°F.
	Deasphalted Oil	about 955°F. and above

A portion of heavy vacuum distillate and deasphalted oil were extracted with furfural at conditions approximating the following:

20	Solvent Dosage	Temperature	Raffinate Yield
	Heavy Vacuum Distillate	150%	220°F. about 69%
	Deasphalted Oil	300%	220°F. about 80%

25 These fractions had the following approximate properties:

30	Unextracted		Extracted		Wt. % Aromatics
	Wt. % Aromatics	API Gravity 60°F	Conradson Carbon	API Gravity 60°F	
Heavy Vacuum Distillate	50	22	—	37	29
Deasphalted Oil	52	22	1.9	—	26

EXAMPLE VIII

A lube distillate approximating a 500 neutral fraction which had been hydrocracked according to the procedure described in U.S. Pat. No. 2,960,458 at about 735° F. and a L.H.S.V. of about 1 was then solvent extracted in a 7-stage known simulated counter-current extraction procedure (i.e., using separatory funnels according to the procedure described in the article "Bench Scale Liquid Extraction Techniques" by Edward G. Scheibel, INDUSTRIAL AND ENGINEERING CHEMISTRY, Vol. 49, No. 10, October 1957, pp. 1679-1684) using a furfural dosage of 200 percent and a temperature of about 80° F. A comparison of the 60 spectral curves of the extracted and unextracted oils from solutions thereof in isoctane shows that the furfural extraction has reduced the amount of condensed ring polynuclear aromatic compounds containing three or more rings.

EXAMPLE IX

A series of runs were carried out as follows:

The materials of the foregoing character were blended to prepare comparative feeds for hydrocracking as follows:

55	Feed Type No. 1 (i.e., Unextracted)	Feed Type No. 2 (i.e., Extracted)
Light Vacuum Distillate, %	24	29
Heavy Vacuum Distillate, %	29	—
Deasphalted Oil, %	47	—
Extracted Heavy Vacuum Distillate, %	—	24
Extracted Deasphalted Oil, %	—	47
Aromatic Content, %	50	37
API Gravity, 60°F.	24	28
IBP	694	706
5%	755	762
10%	784	791
50%	917	940
E.P.	1030	1030
Receiver, %	75	67
Conradson Carbon, wt. %	1.0	—
Viscosity at 100°F.	217	145
Viscosity at 160°F.	41	35
Viscosity at 210°F.	16	15
Waxy V.I.	79-80	112-113
V.I. dewaxed to 0°F.	—	—
pour point	59	about 86

The blended charges of the foregoing character were hydrocracked at conditions approximately as follows:

Catalyst Composition	Feed Type No. 1 Nickel sulfide tungsten sulfide in about a 1:1 metals ratio on a silica alumina base (Ratio on a molar basis)	Feed Type No. 2 5	Initial Color	Final Color	Haze	Sludge
			70 N	100 N	200 N	
Catalyst Temperature (Avg.)	755	Same	0.25	4.25	hvy. med.	hvy.
Space Velocity (L.H.S.V.)	0.5	Same	0.50	4.25	hvy. medium	
Hydrogen Consumption (100% Purity) SCF/BBL	1000	800	1.25	4.50	hvy. medium	

Typical results on a dewaxed basis were as follows:

Yield, based on Vol. % charge to hydrocracker	39.4	45.7
Yield, based on Vol. % of crude	9.6	9.1
V.I. Range	105-115	102-110

That the hydrocracked and dewaxed product was then solvent extracted in the simulated countercurrent 7-stage procedure described in Example VIII with furfural at about 120° F. using a solvent dosage of about 100 percent. The stabilized

Product fraction	Feed type No. 1			Feed type No. 2		
	Color			Color		
	Initial	Final	Sludge	Initial	Final	Sludge
100 N	0.75	2.00	Lt. med.	0.25	2.0	V. lt.
200 N	0.75	1.75	V. lt.	0.50	2.0	None
500 N	1.5	2.25	Haze	1.25	3.25	None
Brightstock	—	—	—	7.0	7.50	None

For further comparison purposes the typical stability characteristics of unstabilized hydrocracked product of Feed Type No. 2 were as follows:

	Color		
	Initial	Final	Sludge
100 N	0.75	7.00	Lt. Med.
200 N	1.25	7.00	Lt. Med.
500 N	2.25	6.00	Light
Brightstock	(Too dark)	(Too dark)	Light

An analysis was made for the typical aromatic content of the charge to the stabilizing extraction and of the stabilized lube product (i.e., the raffinate) and in one case of the extract, the results were as follows:

Aromatic, % (approx.)	Feed Type	Feed Type
	No. 2	No. 1
Charge	15.7	10.8
Raffinate	14.4	10.5
Extract	—	51
Total Raffinate	97	97
Yield, % (approx.)		

EXAMPLE X

A blend of light vacuum distillate and partially furfural extracted heavy vacuum distillate (i.e., similar to that defined in Example IX from a Lagomedio crude were hydrocracked according to the procedure in U.S. Pat. No. 2,960,458 at about 750° F. and a L.H.S.V. of about 1. The hydrocracked product was then solvent extracted with phenol in a 3-stage simulated countercurrent extraction in which the temperature was maintained in the range of about 120°-130° F. and a solvent dosage of about 75 percent was employed.

The raffinate was then tested for stability in the ASTM D 1500 test along with a standard and the results were as follows:

Sample	Initial Color	Final Color	Haze	Sludge
Hydrocracked Oil				
70 N	0.25	4.25	hvy. med.	hvy.
100 N	0.50	4.25	hvy. medium	
200 N	1.25	4.50	hvy. medium	
Extracted (or stabilized) Oil				
70 N	0.25	2.50	med.	light
100 N	0.25	2.00	med.	light
200 N	0.25	1.25	med.	v. lt.
360 N	3.00	3.50	med.	light
Yield (total raffinate, approx.)				97%

In the foregoing examples the final solvent extraction to achieve stability of the hydrocracked lube does not significantly alter the V.I. of the hydrocracked lube.

- 15 The invention claimed is:
1. A process of preparing lube oils with a viscosity index of at least 115 on a dewaxed to 0° F. pour point basis and having high quality and sludge-forming properties which comprises in combination in the following sequence, hydrocracking a suitable lube oil fraction having a viscosity index of from about 60 to 100 on a dewaxed to 0° F. pour point basis with hydrogen at pressures above about 1,500 p.s.i. and temperatures above about 650° F. in the presence of a lube oil hydrocracking catalyst, and subsequently selectively extracting said hydrocracked lube oil fraction by serially extracting same in at least two stages with a solvent selected from the class consisting of furfural, acetophenone, acetonitrile, nitrobenzene, aniline, 2,2'-dichlorodiethyl ether, dimethylsulfoxide and phenol, at a solvent to oil ratio not in excess of about 2:1, at a temperature in the range of about 0° to 300° F., and controlling the extraction temperature and solvent dosages within said ranges to provide for a raffinate yield of approximately 97 percent with the particular solvent employed.
  2. The process of claim 1 wherein the solvent is furfural.
  3. The process of claim 2 wherein the hydrocracking is carried out at a temperature of from about 735° F. to about 825° F. and a pressure of at least about 2,500 p.s.i.
  4. The process of claim 3 wherein the number of extraction stages is not less than three and the extraction temperature is in the range of 0° F. to about 250° F.
  5. The process of claim 4 wherein the lubricating oil stock is dewaxed after the hydrocracking step and before the solvent extraction step.
  6. The process of claim 5 wherein the ratio of furfural to lubricating oil in the solvent extraction step is in the range of about 0.25:1 to 2.0:1.
  7. The process of claim 6 wherein the extraction temperature is from 0° to 150° F.
  8. The process of claim 7 wherein the hydrocracking is carried out at a temperature of from about 735° F. to about 825° F. and a pressure of at least about 2,500 p.s.i.
  9. The process of claim 8 wherein the number of extraction stages is not less than three and the extraction temperature is in the range of 0° F. to about 250° F.
  10. The process of claim 9 wherein the lubricating oil stock is dewaxed after the hydrocracking step and before the solvent extraction step.
  11. The process of claim 10 wherein the ratio of solvent to lubricating oil is in the range of about 0.25:1 to 2.0:1.
  12. The process of claim 11 wherein the solvent is phenol.

13. The process of claim 11 wherein the solvent is acetophenone.

14. A process of preparing lube oils with a viscosity index of at least about 100 on a dewaxed to 0° F. pour point basis and having high quality and sludge-forming properties which comprises in combination in the following sequence, hydrocracking a suitable lube oil fraction having a viscosity index of below about 100 on a dewaxed to 0° F. pour point basis, with hydrogen at pressures above about 1,500 p.s.i. and temperatures above about 650° F. in the presence of a lube oil hydrocracking catalyst, the severity of said hydrocracking being sufficient to increase the viscosity index of said suitable lube oil fraction at least about 24 viscosity index units, and subsequently selectively extracting said hydrocracked lube oil fraction by serially extracting same in at least two stages with a solvent selected from the class consisting of furfural, acetophenone, acetonitrile, nitrobenzene, aniline, 2,2'-dichlorodiethyl ether, dimethylsulfoxide and phenol, at a solvent to oil

ratio not in excess of about 2:1 at a temperature in the range of about 0° to 300° F., and controlling the extraction temperature and solvent dosages within said ranges to provide for a raffinate yield of approximately

5 97 percent with the particular solvent used.

15. The process of claim 14 wherein the lube oil fraction being fed to the hydrocracker has a viscosity index of from about 60 to 100 on a dewaxed to 0° F. pour point basis.

16. The process of claim 15 wherein the solvent is furfural.

17. The process of claim 16 wherein the number of extraction stages is not less than three.

18. The process of claim 17 wherein the ratio of furfural to lubricating oil in the solvent extraction step is in the range of 0.25:1 to 2.0:1.

19. The process of claim 19 wherein the hydrocracked lube product has a viscosity index of at least 115.
